CARTON

Charles J. Chaplin, South Portland, Maine, assignor to Chaplin Corporation, South Portland, Maine, a corporation of Maine

Application April 14, 1950, Serial No. 9,226

Term of patent 14 years

(Cl. D58—12)

To all whom it may concern:

Be it known that I, Charles J. Chaplin, a citizen of the United States of America, residing at South Portland, in the county of Cumberland and State of Maine, have invented a new, original, and ornamental Design for a Carton, of which the following is a specification, reference being had to the accompanying drawing, forming part thereof.

In the drawing:

Fig. 1 is a side elevational view of a carton, showing my new design;

Fig. 2 is a partial top plan view thereof, one half of the article being omitted for convenience of illustration;

Fig. 3 is a fragmentary cross sectional view taken on the line 3—3 of Fig. 1.

I claim:

The ornamental design for a carton, as shown.
CHARLES J. CHAPLIN.
